UNITED STATES PATENT OFFICE.

THOMAS J. JOHNSTON, OF WHITE PLAINS, NEW YORK.

FASTENER-INSERTING DEVICE.

Application filed April 26, 1923. Serial No. 634,814.

To all whom it may concern:

Be it known that I, THOMAS J. JOHNSTON, of White Plains, Westchester County, New York, have made certain new and useful 5 Improvements in Fastener-Inserting Devices, of which the following is a specification.

My present invention relates to fastener inserting devices for attaching fasteners to 10 fabrics, leather or the like, particularly where there are several layers of the material. It is particularly adapted to setting blind eyelets in shoe uppers, where there are several assembled layers of lining and 15 leather. While that is its principal utility, the principles here disclosed may be employed in securing other fasteners to some of several layers of material; some of the claims forming part of this specification are 20 so phrased, and are intended to cover such other applications of the invention. The principal parts employed are a set for upsetting the skirt of the eyelet, where the device is so used, which has the usual tapered 25 portion for that purpose; another member movable relative to the set, which is preferably a sleeve, though it need not necessarily surround the set; means movable relative to the set for separating two of the layers 30 of material so as to provide a space in which the flange which the set forms from the skirt of the eyelet curls over without engaging the outer separated layer, which means is usually one or more levers pivoted in the 35 sleeve, and operated by a cam surface on the punch when the sleeve and punch move relatively, though other arrangements may be employed. Some means of returning the parts to normal position when the set is 40 retracted is desirable, for which springs may be used. The device is positively actuated in its operation, which is to be preferred, as the action does not then depend, as in some other devices, upon the resilience of the 45 leather or other material; but the layer is positively raised and after the eyelet is set is pressed down into place. In practice the layer moved is the outer one, and it is lifted by the levers as the work is commonly done; 50 I prefer to use the term "separated" in the claims, to cover inversions or like variations.

The accompanying drawing shows an embodiment of my invention in one form, being a central vertical section of my improved device, on a large scale.

The set which upsets the eyelet, which it

is unnecessary to show, bears in general the reference letter A, with various indices. The conoidal part for upsetting is marked A¹; A² is the tapered shank for insertion in the machine commonly employed; A³ a collar; A⁴ the shaft of the set, A⁵ the cam for operating the levers; while at A⁶ I show that the tip may be inserted in the shaft by a screw-thread, thus making it renewable, and saving expense in case of breakage. As it is small, it may be made of good steel without undue cost.

B is the member carrying the levers, which is preferably a sleeve, and may be formed integral if desired, as the removable tip permits the insertion of the set from above, after the levers are secured in place.

C C' are the levers for separating the layers of material, also not shown. These are pivoted respectively at c c', and are preferably elbow shaped, the toes C² C² being somewhat wedge-form. Also it is best to make the levers short and pivot them near the bottom of the sleeve, as this makes the radius of the arc which they describe small, and thus makes them lift at their outer ends more quickly, relative to their lateral swing, thus lifting the outer layer of leather or fabric promptly.

D D' are springs for returning the levers to their normal or illustrated positions as the set is lifted.

E is a spring between the sleeve and the collar A³ for restoring the normal relation between the set and sleeve when the device is raised. A pin or set-screw, not shown but commonly employed in such constructions, limits the relative motion of the punch and sleeve.

The number of levers employed may vary with the character of the work. With ordinary leather two are sufficient; with very thin tawed skins three may be needed, but more may be used, if desired, though not generally required.

I have drawn the view of the device on a much exaggerated scale, as is apparent, so as to make it easily comprehended.

Having thus described my invention, what I claim is:

1. A device for setting blind eyelets in a selected part of several layers of material, comprising a set provided with a setting shoulder adapted for insertion in the material for spreading the skirt of an eyelet between two of the layers, and means carried

by the device and movable relatively to the set for separating the two layers to permit the spread portion of the eyelet to pass between them.

- 5 2. A device for setting blind eyelets in part of several layers of material, comprising a set for upsetting the skirt of the eyelet adapted to be inserted in the material, a lever carried by the device for separating 10 two of the layers to permit the upset skirt to pass between them, and means for operating the lever.
- 15 3. A device for setting blind eyelets in some of several layers of material, comprising a set for upsetting the skirt of the eyelet adapted to be inserted in the material, one or more levers for separating one of the layers of material from the adjacent one, and means operated by the set for actuating the 20 levers.

4. A device for setting blind eyelets in some of several layers of material, comprising a set having an upsetting portion adapted for insertion in the material, one or 25 more levers for separating two of the layers of material to permit the upset part of the eyelet to pass between them, and a cam for operating the levers.
- 30 5. A device for setting blind eyelets in some of several layers of material, comprising a set having an upsetting surface adapted for insertion in the material, one or more levers for separating two of the layers, and a cam upon the set for operating the levers.

- 35 6. A device for setting fasteners in some of several layers of material, comprising a set having an upsetting surface for insertion in the material and for clinching a fastener between two of the layers, a member movable relative to the set, one or more levers carried by said member for separating the two layers to provide space for the clinched portion of the fastener, and means for operating the levers.

- 40 45 7. A device for setting blind eyelets in some of several layers of material, comprising a set having an upsetting surface capable of passing through at least one layer of material, a sleeve, one or more levers for separating two of the layers of material, the le-

vers carried by the sleeve, and a cam actuated by the set for operating the levers.

8. A device for setting a metal part in some of several assembled layers of material, comprising a set having an upsetting surface capable of passing through at least one layer of material, a member movable relative to the set, one or more levers carried by the member and acting to separate two of the layers of material, and a cam on the set for actuating the levers.

9. A device for setting metal parts in some of several layers of material, comprising a set having a tapered setting portion capable of passing through at least one layer of material, a sleeve movable relative to the set, one or more levers carried by the sleeve and acting to separate two of the layers of material, a cam on the set for actuating the levers when the set and sleeve have relative motion, and means for returning the levers to position when the set is withdrawn.

10. A device for setting metal parts in some of several layers of material, comprising a set having a tapered portion for upsetting the part to be set, the tapered portion adapted for insertion in at least a part of the material, a sleeve movable relative to the set, means operated by the relative movement of the sleeve and set for separating two of the layers, and springs for returning such means to normal position when the set is withdrawn.

11. A device for setting blind eyelets comprising a set, a sleeve, levers carried by the sleeve, and a cam surface upon the set for operating the levers by the relative movement of the sleeve and set; the levers being of short radius, so that the arc described by them gives a large lift relative to their lateral swing.

12. A device for setting blind eyelets comprising a set, a member movable relative to the set, one or more levers of short radius carried by the member, and means, actuated by relative movement of the set and member, for operating the levers.

In testimony whereof I have hereunto signed my name this 9th day of April 1923.

THOMAS J. JOHNSTON.
